Primary Examiner—Ian Simmons*Assistant Examiner*—Christopher Lee*(74) Attorney, Agent, or Firm*—Nixon & Vanderhye P.C.CLAIM

The ornamental design for a front face of headgear for a mask, as shown and described.

DESCRIPTION

FIG. 1 is a front view illustrating a front face of headgear for a mask according to my design.

The thickness of the headgear forms no part of the claimed design.

Where included, broken lines showing environment or structure of the headgear are for illustrative purposes only and form no part of the claimed design.
